By his Patent Attorney

Mr. Wallace White

UNITED STATES PATENT OFFICE.

GEORGE DE CAIROS-REGO, OF SYDNEY, NEW SOUTH WALES, AUSTRALIA.

ELECTRIC VIBRATOR.

Application filed April 27 1921. Serial No. 464,939.

To all whom it may concern:

Be it known that I, GEORGE DE CAIROS-REGO, a subject of the King of Great Britain, residing at Sydney, in the State of New 5 South Wales and Commonwealth of Australia, have invented new and useful Electric Vibrators, of which the following is a specification.

This invention relates to a new and improved electric vibrator having an electro-magnet and an armature so mounted as to induce, when current is passing through the instrument, mutually reciprocal motion, the object of the invention being to provide a 15 device of this character which is not only of great value as a therapeutic instrument in massage treatment, but is capable of a variety of other uses, such, for instance, as the treatment of violins and similar musical instruments for producing greater responsiveness or flexibility.

The novel vibrator comprises an electro-magnet and vibrating plate of metal and preferably of springy steel. The vibrating 25 plate which is not so flexible as to be readily attracted or drawn to the electro-magnet is clamped or fastened at one end within a suitable yoke or back so as to form the armature of the electro-magnet which is affixed to one leg of and within a U shaped frame or band both ends of which are also fastened to said back one being adjustable inwardly and outwardly thereof, so that the 30 magnet may be regulated in relation to the armature by slightly drawing in said end or letting it out. And this leg carries an adjusting screw controlling a contact spring secured to said back and projecting within said frame and within contact distance of 35 another contact projecting from the extension of said back constituting a make and break. Suitable terminals for electrical leads from a source of electrical energy say a battery or other generator are provided on 40 the back, the circuit being through the coils of the electro-magnet, thence through the U frame or a lead to the make and break and back to the source of energy.

If desired the make and break springs 50 may be removably affixed, being carried by a removable block adapted to fit into complementary slots in the back and so that one spring will contact with a keeper or slot contact on the projection of the back and in circuit with the electrical energy and the other

spring will be in contact with the U frame.

Upon the inner face of the fixed leg of the U frame and adjustable inwardly and outwardly of the back is a regulating block to adjust as desired the flexibility or rigidity 60 of such frame which should offer a greater resistance to movement than the armature and in relation to the armature the lower contact spring should possess a higher frequency than that adopted for the vibration 65 of the armature.

I have found that, while the range of frequency of vibrations of the armature may vary considerably, a satisfactory frequency of vibration can be secured by a plate of 70 springy steel about $1\frac{3}{4}$ inches wide $\frac{1}{16}$ of an inch thick and of a vibrating length of from 3 to 4 inches.

A cover of suitable material say thin metal may be and preferably is provided 75 and is affixed to the back enclosing the parts but with the free end of the armature protruding therethrough.

For convenient use in massage or therapeutics said free end is adapted to carry an 80 ordinary imparting cushion generally of rubber and in the form of a cup which is applied as ordinarily to the part of the body to be massaged or treated.

For convenience in manipulating the vibrator, a handle is affixed to the other side of the yoke or back and has a central passage for electrical leads.

For the purpose of preventing the vibrator "travelling" when vibration is being 90 imparted to violins and like instruments the vibrator is preferably balanced upon a supporting cushion or cup preferably of rubber affixed to the leg of the U frame carrying the electromagnet or to the cover 95 when there is one.

It is convenient to make the yoke or back of non-conducting material say wood and the U frame or band of metal, say aluminium, which may be ribbed or "dished" 100 longitudinally for strength though such frame may be made of thin wood or other material and if such be non-conducting it is then necessary to provide a lead from the electro-magnet to the make and break.

In order that a practical application of the invention may be readily understood the same will now be described with reference to the accompanying drawings in which Figure 1 is a longitudinal sectional eleva- 110

tion of a vibrator constructed in accordance with the present invention. Figure 2 is a back end elevation thereof with the handle removed; Figure 3 is a plan view of the **U** frame before bending with the positions of the electro-magnet and regulating block being indicated in dotted lines; Figure 4 is a plan view of the vibrating plate or armature; Figures 5 and 6 are respectively 10 a side and a front elevation of a section of the back; and Figure 7 is a side elevation of the removable block carrying the make and break springs.

To the back 5 preferably of non-conducting material, say wood, and having clamping bolts 6 therethrough with nuts 7 and preferably a handle 8 with leads passage 9 is clamped or affixed the vibrating plate or armature 10 which is further clamped with 20 in an inward projection 11 from the back 5 by bolts 12 insulated from the armature. Said projection carries the contact spring 13 which is in contact with one or both of the fastening bolts 12 insulated from the armature 10 and connected to a lead 14 from the battery. Also affixed to the back 5 is the **U** frame 15 having one end 16 fast with a resistance or regulating block 17 slidably adjustable thereon and retained in position by bolt 18 through the back 5 and having on its protruding end nut 19. Said frame passes through slot 20 in the armature 10 and has its other end adjustably affixed to the back 5 by a tongue 21 taking through 30 an orifice 22 in said back 5 and having on its protruding end nut 23.

On and within said **U** frame 15 is affixed the electro-magnet 24 in circuit with one lead 25 say through binding post 26 and 40 with said frame 15 by lead 27 and by said frame 15 with spring contact 28 in contact with said frame and clamped within the back 5 and projecting inwardly therefrom to above the contact spring 13 where it is 45 adjusted or controlled by set screw 29 preferably in an insulated seat 30 affixed to the frame 15.

When the make and break springs 28 and 13 are to be removable they are carried by 50 a removable metal block consisting of upper section 38 having orifice for the tongue 21 of the **U** frame 15 and lower section 39 insulated from one another by material 40 and held together by pins or dowels 41 of 55 non-conducting material. The spring 13 carries thereon a contact piece or filler 42 to engage with the slot contact and keeper 43 on the projection 11 of the back 5 as the block is pushed into position through 60 slot 44 in the back 5. Said keeper is in circuit with the electrical energy and is larger than the thickness of the spring 13 to allow for clearance of the contact point thereon. The other spring 28 is in contact with the 65 **U** frame 15 through the upper section 39

of the block which receives the tongue 21 of said frame when the block is placed in position. This block is firmly gripped and retained in place as the nuts 7 are tightened on the bolts 6.

Enclosing the parts is a cover 31 fastened to the back 5 in any convenient manner and having end slot 32 through which the free end 33 of the armature 10 protrudes.

For use in massage there is removably affixed to said end 33 by means of a suitable extension, either straight or angular, as 34 an ordinary imparting or contact cushion 35 or other desired applicator or imparter, and for convenience in applying vibration to a violin or like instrument and preventing the vibrator travelling, an imparting or contact cushion 36 is affixed to the exterior of the cover 31 at about the point of balance.

The circuit from the source of electrical energy indicated at 37 is to the electro-magnet 24 through the frame 15 thence through the make and break 28 and 13 back to the source 37.

In use the circuit being completed by connecting the leads 14 and 25 to a source of electrical energy 37 and adjusting the make and break 28 and 13 by the screw 29 the electro-magnet 24 being energized exerts its force upon and sets in motion the armature 10, which, although resilient, yet is sufficiently stiff to somewhat resist such force and induces a reciprocal motion of the magnet towards it by which motion the frame 15 and the screw 30 are moved, the spring contact 28 eventually passing from the range of the spring contact 13 whereupon the circuit is broken and the frame regains its normal position when the contact 28 being pressed towards the contact 13 the circuit is again closed with like effect the continuation of which intermittent action keeps up the vibrations of the frame 15 and also the armature 10 which vibrations may be imparted to an article by resting the vibrator thereon by means of the cushion 35 or such vibrations are imparted to a body or surface to be treated by moving the cushion 35 on the armature 10 on said body or surface the cushion providing a smooth flexible contact and smooth transmission of the vibrations.

I claim:—

1. An electric vibrator, comprising an electromagnet, contact devices for closing an electric circuit through said magnet, a vibratory armature in the field of the magnet, and means for imparting to the magnet a vibratory movement relative to said armature when current passes through the magnet.

2. An electric vibrator, comprising a flexible frame, an electromagnet carried by said frame, contact devices for closing an

electric circuit through said magnet, a vibratory armature in the field of the magnet, said frame and armature being adapted to vibrate in unison when current

frame, and a stiff vibrating armature extending from said back within and protruding through said frame and set in the field of the electro-magnet.

5 passes through the magnet thereby to alternately open and close the contact devices.

3. An electric vibrator comprising a back, a flexible frame extending therefrom, an electro-magnet on said frame in circuit with 10 electrical energy through make and break devices consisting of a spring contact projecting from said back and an adjustable spring contact projecting from said back, said devices adapted to be operated by 15 movement of said frame, and a stiff vibrating armature extending from said back within and protruding through said frame and set in the field of the electro-magnet.

4. An electric vibrator comprising a back, 20 a flexible frame extending therefrom, an electro-magnet on said frame in circuit with electrical energy through make and break devices consisting of a spring contact and an adjustable spring contact projecting from 25 a removable section of said back, said devices adapted to contact with parts or contacts in circuit with the electrical energy and to be operated by movement of said

5. In an electrical vibrator having an electro-magnet and an armature, a flexible frame carrying said electro-magnet, make 35 and break devices independent of and insulated from the armature and comprising a spring in circuit with one pole of energy and an adjustable spring in circuit through the electro-magnet with the other pole of 40 energy and operated by movement of said flexible frame.

6. An electric vibrator, comprising an electro-magnet, means for energizing said magnet, a vibratory armature in the field 45 of the magnet, a resilient support for said magnet, said armature being adapted to induce a vibratory movement of said support thereby to reciprocate the magnet toward and from the armature, and circuit- 50 closing means actuated by the vibration of said support to open the circuit through said magnet.

Dated this seventh day of March, A. D. 1921.

GEORGE DE CAIROS-REGO.
